UNITED STATES PATENT OFFICE.

VICTOR LÉON CAZES, OF NEUILLY-SUR-SEINE (SEINE), FRANCE.

SAFETY DEVICE FOR GAS-PRODUCERS ADAPTED TO ACT AS GAS FILTERS, COOLERS, AND DRIERS.

1,364,833.

Specification of Letters Patent.

Patented Jan. 4, 1921.

Application filed November 14, 1918. Serial No. 262,619.

To all whom it may concern:

Be it known that I, VICTOR LÉON CAZES, citizen of the Republic of France, residing at 128 Rue Perronet, Neuilly-sur-Seine, Seine, in 5 the Republic of France, have invented new and useful Improvements in Safety Devices for Gas-Producers Adapted to Act as Gas Filters, Coolers, and Driers, of which the following is a specification.

10 This invention relates to a safety device acting also as a cooling, filtering and drying apparatus which is adapted to be interposed between the gas producer and the motor on automobiles provided with a gas producer 15 and by means of which two essential results are obtained as follows: first, any back firing to the gas producer is prevented by means of a bundle of tubes having a length and a diameter such that flames are checked 20 thereby and secondly the gases are suitably cooled, filtered and dried before they reach the motor.

The annexed drawing, given by way of example, is a longitudinal section of an apparatus 25 constructed in accordance with the invention.

Referring to the drawing, the apparatus comprises two parallel elongated casings B and E arranged one above the other and connected to each other by means of a tubular bundle T. The upper casing or box, B, is provided with two necks K and I for the inlet and outlet of the gases. It is closed at one 30 end by a door A, which has a gas tight joint and carries a horizontal rod upon which partitions C, C¹ and C² are secured. Said partitions have a snug fit in the casing and divide the same into three chambers, or compartments a, b, f. The intermediate partition 35 C¹ is cut away at the top so as to leave a free passage for the gas.

The lower box or casing E is closed at the bottom by a hermetically closing lid F, upon which is secured a vertical partition C⁴ 45 which divides the casing into two chambers or compartments d and e.

From the upper wall of the lower casing hang two partitions C³ and C⁵ which are cut away at their lower edge and are located in 50 vertical alinement with the partitions C and C² in the upper casing A, B, D, O.

The compartments or chambers a, b, f, d, e are filled with a spongy material g.

The upper and lower casings are connected to each other as already explained by a

bundle of tubes T which are secured at one end to the bottom wall of the upper casing and, at the other end to the upper wall of the lower casing. The length and diameter of said tubes are so selected that any back firing through the same is effectively prevented. As shown in the drawing, the tubes T form a connection between the compartment a and the compartment d, between the compartment b and the compartments d and e and between the compartment f and the compartment e, respectively.

The gas being fed to the apparatus through the neck k enters first the compartment a in the upper casing and permeates through the spongy material in said compartment where it is filtered and dried. It then passes through the first series or bundle of tubes T in which it is subjected to a first cooling, and reaches the compartment d in the lower casing where it is filtered and dried a second time by its contact with the spongy material in the same and so on through all the other compartments in both casings and the tubes as indicated by the arrows, the gas being finally discharged at I. The number of tubes T varies according to the power of the motor.

A fan or any other similar apparatus V may be used to cool the tubes.

By removing the lid or door A from the upper casing, the rod secured to the same and the partitions C, C¹, C² are pulled out at the same time so that an efficient cleaning is effected. In the same manner, by taking off the lid F from the lower casing, the tubes may be easily cleaned. All these operations can be effected very rapidly without taking apart either the piping or the apparatus.

Various details of construction may obviously be modified without departing from the invention.

Having now described my invention what I claim as new and desire to secure by Letters Patent is:

1. A safety device for preventing back firing in automobiles provided with a gas producer, said device comprising in combination an upper casing, an inlet and an outlet for the gas on said casing, a lower casing, bundles of tubes affording communication between the upper and the lower casing, and means in the upper and lower casings to cause the gases to successively pass through the different bundles of tubes.

2. A safety device for preventing back firing in automobiles provided with a gas producer, said device comprising in combination an upper casing, an inlet and an outlet for the gas on said casing, a lower casing, bundles of tubes affording communication between the upper and the lower casings, means for cooling said bundles of tubes and means in the upper and lower casings to cause the gases to successively pass through the different bundles of tubes.
3. A safety device adapted to act as a filter, a cooler and a drier for the gas delivered by a gas producer, said device comprising in combination an upper casing, an inlet and an outlet for the gas on said casing, a lower casing, bundles of tubes affording communication between the upper and the lower casing, means for cooling said bundles of tubes and means in the upper and lower casings to cause the gases to successively pass through the different bundles of tubes and a filtering and drying medium in both casings.
4. A safety device for preventing back firing in automobiles provided with a gas producer, comprising in combination an upper casing, an inlet and an outlet for the gas on said casing, a door adapted to close said casing at one end, means for holding said door in the closed positions, a rod secured on said door, partitions secured on said rod and dividing the casing into compartments, a lower

casing, a removable lid adapted to close said lower casing at the bottom, partitions adapted to divide said lower casing into compartments, bundles of tubes extending respectively from one compartment in the upper casing to a corresponding compartment in the lower casing, some of the said partitions being cut away so as to provide an uninterrupted passage for the gas from the inlet to the outlet through all of the different compartments and bundles of tubes, successively, means for cooling said bundles of tubes and a filtering and drying medium in the said compartments.

5. A safety device for preventing back firing in automobiles provided with a gas producer, said device comprising in combination an upper casing, an inlet and an outlet for the gas on said casing, a lower casing, bundles of tubes affording communication between the upper and the lower casing, means in the upper and lower casings to cause the gases to successively pass through the different bundles of tubes and a fan adapted to set up a circulation of air about the said tubes.

In testimony whereof I have signed my name to this specification in the presence of two subscribing witnesses.

VICTOR LÉON CAZES.
